UNITED STATES PATENT OFFICE.

GEORGE MELVIN WILSON, OF CALGARY, ALBERTA, CANADA.

WIRE STRETCHER AND PULLER.

Application filed November 15, 1920. Serial No. 424,204.

To all whom it may concern:

Be it known that I, GEORGE MELVIN WILSON, a subject of the King of Great Britain, a resident of the city of Calgary, Province 5 of Alberta, Dominion of Canada, have invented certain new and useful Improvements in Wire Stretchers and Pullers, of which the following is a specification.

This invention relates to improvements in 10 wire stretchers and pullers, and the objects of the invention are to provide a wire puller which can be advantageously utilized in fencing and whereby the several strands of 15 wire may be pulled up to the desired tightness before being fastened, to so arrange the puller that the action will be a step by 20 step one, that is to say, the pulling and stretching action after being commenced will continue step by step until the required tension of the fence wire has been obtained and before the loose ends of the wire are 25 connected, and to simplify the arrangements of the several parts and adapt them to better perform the functions required.

With the above and other objects in view, the invention consists essentially of the improved construction particularly described and set forth in the following specification and accompanying drawings forming part 30 of the same.

In the drawings:

Figure 1 is a perspective view of the improved wire puller and stretcher.

Figure 2 is a side elevation of the same.

Figure 3 is an elevation of the opposite side of the wire puller to that shown in Figure 2.

Figure 4 is a side elevation of one of the wire engaging elements.

Figure 5 is a perspective view of one lever of the wire engaging element.

Figure 6 is a perspective view of the other lever of the wire engaging element.

Figure 7 is an end view of that lever of 45 the wire engaging element in Figure 6.

Like characters of reference refer to like parts in the several figures.

Referring to the drawings: A represents the improved wire puller and stretcher comprising a plurality of wire engaging elements B, C and D, each of the elements being connected by spring bales 4, 5 and 6, to the lever B.

Each wire engaging element consists of 50 a pair of pivoted levers 8 and 9, the former of which is longer than the latter and is pro-

vided with cutaway portions 10 forming a suitable shoulder 11 and this cutaway portion 10 carries a hinge pin 12. A retaining clip 13 is secured to the back face of the 60 lever 8, and adjacent to the end of the lever remote from the cutaway portion 10 an orifice 14 is provided.

The lever A is of substantially angle shaped with the lower face 15 of one of the 65 arms formed curvilinear and this arm is cut away to form a curvilinear shoulder which is provided with a plurality of serrations 16, and adjacent to this shoulder an orifice 17 is provided with which the hinge pin 12 engages.

By referring to Figure 6 it will be seen that the lever is eccentrically pivoted relatively to the lever 8, so that the serrated shoulder 16 will be brought into contact with 75 the shoulder 11 of the lever 8 during the rotating of the levers 8 and 9 towards each other.

The lever 9 is provided with a pair of orifices 18, and the orifices 14 and 18 are engaged by the ends of the bails 4, 5 and 6, and by providing two orifices 18 in the lever 9, an adjustment of the movement of the lever 9 to the lever 8 is thus obtained.

The bails have their ends offset to pass 80 through the orifices 14 and 18, and this prevents the levers 8 and 9 from turning and holds the levers in a firm position.

In the embodiment illustrated the centre pulling member C is the only one in which 90 the lever 9 is provided with a pair of orifices, and in the pulling elements B and D only one orifice 18 is shown.

The bails 4, 5 and 6 are made of spring material so that when no pulling force is 95 exerted on the said bails they will have a tendency to open and thereby rotate the levers 9 and 8 relatively to each other thereby disengaging the serrated shoulder 16 from the shoulder 11, and consequently liberating the wire to be stretched located between the said shoulders.

When the wire puller is in use, it is arranged with two of the pulling elements, B and C on one side of the lever E and the 105 third pulling element D, on the other side of the lever, and in this position if there is no force applied to the lever E the levers 8 and 9 will open under the action of the spring bales 4, 5 and 6 and will assume the 110 position shown by the dotted lines in Figure 4.

To obtain the necessary leverage, the lever E may be constructed to receive a removable handle of suitable length, which can be removed when shipping the wire puller and stretcher.

This allows clearance between the serrated shoulder 16 and the shoulder 15 to press the wire to be stretched therebetween. The ends of the wire will be arranged in alignment and one end of the wire will pass through the elements B and C, while the other end will pass through the pulling element D.

As the lever E is now actuated it will cause two of the elements to be pulled towards each other, while the other element will pass loosely over the wire being stretched, and will engage with the wire when a reversal of the action of the lever E takes place. This operation will be better understood from the following description.

The pulling elements B and D will be primarily positively engaged with the wire to be tightened on the first movement of the lever E, and although the wire passes through the pulling element C it will not be held therein because there will be no pull applied to the levers 8 and 9 of this pulling element C during the first operation of the lever E to pull the pulling elements B and D towards each other and during this action the pulling element C will be in the position shown by the dotted lines in Figure 4.

It will be noticed that when the lever E is actuated to pull the pulling elements B and D together then no pull is applied to the pulling element C which is given a translatory movement along the wire, but as soon as the reverse motion of the lever E takes place then the pulling element C will engage with the wire passing therethrough while the pulling element B will be disengaged from the same, so that on the continued oscillating motion of the lever E the ends of the wire will be pulled up step by step towards each other, until tensioned to the desired extent when the adjacent ends may be joined.

It should be particularly noted that the pulling element D always has a pull applied thereto and the bale 6 of this pulling element is attached at a point adjacent to the fulcrum about which the action of the lever E takes place, so that consequently the pulling element C is always held in engagement

with the wire A the bailes 4 and 5 are attached to the lever E on the opposite side of the bale 6, they consequently have a force applied thereto alternately, the pulling elements carried by the said bailes engage the wire passing therethrough alternately and permit of a step by step action taking place to tighten the wire. The functions of the spring clip 13 is to maintain the levers 8 and 9 open when primarily positioning the wire and also when disengaging the puller from the stretched wire.

From the description it will be seen that I have a wire puller and stretcher which can be utilized when inclosing land with fences, the device being of an extremely simple nature and not liable to go out of repair.

As many changes could be made in the above construction and many widely different embodiments of my invention within the scope of the claim, constructed without departing from the spirit or scope thereof, it is intended that all matter contained in the accompanying specification and drawings shall be interpreted as illustrative and not in a limiting sense.

What I claim as my invention is:

A plurality of wire engaging elements, each comprising a pair of pivoted levers, one of which is longer than the other and provided with a cut-away portion forming a shoulder, a hinged pin to which the other lever is pivoted carried by said cut-away portion, a spring retaining clip secured to the back face of the lever whereby the levers are retained in open position, and an orifice adjoining the lower end thereof, the second of said levers formed in angular shape with a curvilinear shoulder provided with a plurality of serrations adapted to contact with the shoulder of the first lever, an orifice adjacent thereto to engage said hinged pin, a pair of orifices in the second lever whereby an adjustment of the movement of this lever to the first lever is obtained, a spring bale co-acting with each pulling element and having its ends connected to the levers, and an actuating lever having the bales pivoted thereto.

In witness whereof I have hereunto set my hand in the presence of two witnesses.

GEORGE MELVIN WILSON.

Witnesses:

JAMES A. HORNBY,
FRANCES NOBLE.
